UNITED STATES PATENT OFFICE.

LAWRENCE G. HALLBERG, OF CHICAGO, ILLINOIS.

CENTERING FOR CONCRETE WORK.

982,055.

Specification of Letters Patent. Patented Jan. 17, 1911.

Application filed February 13, 1907. Serial No. 357,124.

To all whom it may concern:

- Be it known that I, LAWRENCE G. HALLBERG, a citizen of the United States, residing at Chicago, in the county of Cook and 5 State of Illinois, have invented certain new and useful Improvements in Centerings for Concrete Work, of which the following is a specification, reference being had therein to the accompanying drawings.
- 10 My invention relates to centerings for concrete structures, and its object is to provide an adjustable centering for use in making concrete floors, columns, and partitions or girders.
- 15 The invention consists in the arrangement and construction of parts as hereinafter described and pointed out in the claims.
- In the accompanying drawings which illustrate an embodiment of my invention— 20 Figure 1 is a top plan view of parts employed for making a centering embodying certain features of my invention; Fig. 2 is a view partly in elevation and partly in section on the line 2—2 of Fig. 1 illustrating 25 a construction which may be employed in certain details; Fig. 3 is a detail view partly in side elevation and partly in section showing one of the sides of the centering for making walls or girders; and Fig. 4 is a 30 cross-sectional view of parts of the centering for making columns or pillars, and which may be employed in connection with the other parts.
- In constructing concrete floors, columns, 35 and walls or girders suitable supports are necessary to receive the material and hold it in place while setting, and as heretofore constructed these supports have been of such construction that they were merely temporary 40 and capable of use in one instance and were necessarily disassembled and destroyed when taken apart, so that practically a new one had to be constructed for each floor panel or slab, column, and wall or girder. In the 45 employment of my invention I provide a centering which is in knockdown form so that the same parts may be used over and over again, and which also is adjustable in order to accommodate or provide for different sizes or dimensions in the floor-panels 50 or slabs, columns, and walls or girders.
- In the accompanying drawings Fig. 4 shows a detail of that part of the centering adapted to be filled with concrete to form 55 columns or pillars A, and in the preferred embodiment of the invention it is made ad-
- justable in size or cross-section, it of course being obvious that it may be made of any suitable length to accommodate itself to the distances between the floors or may be made up of several shorter lengths for this purpose or that a single short length may be successively employed as the pillar is built up. As shown in Fig. 4, the frame of the centering for the pillars is made in sections 60 a, which may be of any suitable contour. The adjacent sections are provided with ears a' which are suitably connected together by screw bolts or rods a². In order to adjust the centering to produce pillars of different 65 diameters suitable filling pieces a³ may be introduced between the adjacent sections, it being obvious that the diameter of the centering will be varied according to the number more or less of the filling strips introduced between the sections, these strips preferably being clamped between the ears. Suitable clamping strips a⁴ may be employed, and the ends of the ears are preferably flanged as at a⁵ to form seats for the strips. 70 The strips reinforce the sections and prevent them from springing or bulging out between the bolts and serve as stanchions for ends of girders above.
- The reference letters B and B' indicate 75 suitable stanchions which are adjustable in any suitable manner in order to provide for erecting a centering thereon at different elevations according to the different heights of the floors, etc. In the form shown the 80 stanchions are made in sections, the lower sections b being provided with a series of seats, such as holes or perforations, b' to receive the bolts or rods b² passing through holes b³ in the upper sections. The upper 85 section of each stanchion in the form consists of an oppositely disposed pair of pieces b⁴ of suitable length and of substantially the same width as the associated section b, arranged upon opposite sides of the lower 90 section and provided intermediate their ends with cross-pieces or collars b⁵ surrounding the upper end of the lower section.
- It is obvious that the sections of the stanchions may be adjusted to provide various 95 heights and lengths by adjusting the bolts in different holes in the sections. The upper sections of the stanchions B carry lateral brackets which in the form shown consist of suitable cross-arms b⁶ which are connected to the upper ends of the upper sections in any suitable manner and are braced by.

means of suitable supports b^7 which are seated by shoulders at their lower ends upon the collars b^5 to which they are suitably fastened.

5 The stanchions are erected at suitable distances apart and their brackets support or carry joists C. These joists are adjustable in length and for this purpose preferably are composed of telescopic sections; to this 10 end I provide a suitable pair of lengths or pieces of material c, which are arranged parallel and suitably spaced apart widthwise by any means such as the collars c' to form an intermediate space adapted to receive an 15 associated section c² consisting of a suitable length or piece of material. The lateral parts c form the outer section of each joist and the part c² forms the inner section, these parts being preferably approximately of the 20 same length so that when the sections are entirely telescoped the section c² is within the outer section composed of the parts c, whereby the length of the joist is reduced to a minimum to expedite handling, packing 25 and shipping. The sections may be moved upon each other, as by drawing out or pushing in the interior section c² which slides through the collars c, in order to adjust the length of the joist; in practice the outer section is provided with a pair of collars suitably spaced apart near its outer end in order to render the joist rigid at its joint, although of course this may be obtained by 30 making the collar at the end of the outer section wide enough to provide an extended bearing for the inner section. By this construction an adjustable joist is provided which may be of any suitable length and gives a firm unyielding support in any position 35 of adjustment.

40 A series of cross-beams D are provided, adapted to rest upon the joists, as shown in Fig. 2. These cross-beams are also constructed in adjustable lengths and preferably 45 in the same manner as the joists; the outer section is composed of a pair of pieces d suitably spaced apart and held in position by collars d' and adapted to receive an associated inner section d² which fills the space 50 between the sections d and is movable back and forth within the collars for the purpose of adjusting the length of the cross-beam.

55 The joists and cross-beams provide for the floor-panels or slabs a centering which is in knockdown form and which may be adjusted longitudinally and transversely to provide panels or slabs of varying size or dimensions. When it is used a suitable temporary cover or floor E is laid upon the cross-beams to 60 form a support for the cementitious material while setting.

65 In practice it is preferable to support the strips of sheet metal composing the temporary floor at every three or four inches, and for this purpose I provide floor-slats which

are carried by and run transversely of the cross-beams D, being parallel with the joists C and adapted to fill the spaces between the joists and beams for the purpose of affording more extended support for the sheet-iron 70 sections or strips E employed in making the temporary floor for the concrete. The slats are preferably adjustable in length and for this purpose are composed of relatively sliding or moving sections e and e'. In order to 75 provide for more conveniently and quickly handling the slats I prefer to arrange them in banks or groups, each bank preferably being of such dimensions as to provide a suitable filler between each pair of adjacent 80 joists. For this purpose I connect a plurality of slats together in parallel formation by suitable cross-pieces e² which are attached by screws or other suitable means to the under edges of the slats. One side of each 85 bank will be provided with two or more of these cross-pieces which are adapted to receive and support the associated slats comprising the other side of each bank as clearly shown in Fig. 1. By this construction each 90 bank of floor slats may likewise be adjusted to any suitable length.

95 In using the device as thus far described a series of stanchions are erected to conform to the general outline or contour of the structure desired. In the form shown in Fig. 1 the centering is employed for the purpose of making a floor and it is obvious that when so used the stanchions will be arranged at suitable intervals along the length and width 100 of the space occupied by the floor. The joists C are then placed in position, preferably along the length or longest line of the structure, and the cross-beams D are placed in position transversely upon the joists as 105 clearly shown in Figs. 1 and 2, after which the floor-slats are placed in position upon the cross-beams and parallel to the line of the joists, as clearly shown in Fig. 1. When the parts of the floor-panel centering are 110 thus in position the sheet iron strips E forming the temporary floor for the concrete material are placed in position upon the floor-slats, and the concrete material is then spread upon the floor in the usual manner. 115 It is obvious that as the joists C, cross-beams D, slats and sheet-iron strips are all adjustable in length the floor-panel centering may be employed for various sizes of floor-panels or slabs, the dimensions of which may be 120 varied by altering the length of the joists or cross-beams, or of both.

125 It is of course understood that the floors or partitions are supported or carried by any suitable permanent supports with which the floor-centering is associated temporarily, and to which the material of the floors or partitions is suitably connected. For example, in constructing a floor the 130 panel-centering may be erected to come flush

with the top of the wall or foundation of the first story, and then the concrete is laid over the floor E and the top of the foundation or wall at the same time; while the 5 material is setting a second panel-centering is erected in position on the first floor with its floor flush with the top of the next section of the wall as the latter is completed, and the material for the second floor is put 10 in place; while the material for the second floor is setting the first panel-centering is removed and placed in position for the third floor, and while the material of the third floor is setting the second panel-centering 15 is moved to the fourth floor, this process being repeated for as many stories or levels as desired, the knockdown form of the centering providing for its rapid assembling and dis-assembling for repeated use at different elevations. Where suitable pillars or 20 columns are employed at intervals substantially the same operations are followed, the centering being erected in association with the pillars or supports and flush with their 25 successive elevations substantially in the manner illustrated in Fig. 1, the knockdown form of the centering providing for its use successively and its adjustability providing for its use in locations where the 30 spaces between the pillars or supports vary.

It is obvious that each of the stanchions may carry brackets of such form that adjacent sections of the centering may be carried by the same stanchions, and for this 35 purpose the brackets may be provided at each end in any form adapted to support an associated pair of joists, as illustrated in Fig. 2. In this form the cross-beams of 40 adjacent portions or sections of the centering may extend beyond their associated joists so as to abut or approach more or less, as by extending the opposite cross-beams D of Fig. 2 more or less toward each other.

The general arrangement described may 45 be utilized for the purpose of providing a partition or girder centering extending across between the main walls or supports, as between adjacent pillars A. For this 50 purpose the brackets are provided at their ends with upwardly extending portions or risers b⁸ so that when the joists and cross-beams are placed thereon in the manner shown the structure will provide a trough or channel substantially U-shape in cross-section intermediate adjacent sections or 55 portions of the panel-centering and extending between adjacent supports, as the columns A. A centering for the material of the girder is constructed in this U-shaped trough, and preferably is adjustable both longitudinally and transversely. In the 60 form shown the sides and bottom of the centering are composed of strips or pieces of suitable length, and alternate pieces f are secured to suitable collars f', and the inter-

mediate pieces or sections f² are secured to corresponding collars f³, the arrangement being such that the sections f and f² slide longitudinally upon each other in order that the length of the centering may be adjusted 70 to accommodate itself to different lengths or distances between adjacent columns or supports. Furthermore, in order to provide for making the girders of different width or thickness, the collars f are preferably sectional and adjustable in size; this is suitably accomplished by extending the base f⁴ of one side of the collar and providing it with perforations f⁵ at suitable distances apart and adapted to receive a screw f⁶ or other 75 suitable fastening means upon the other side or portion of the collar, as clearly shown in Fig. 2. The girder-centering is provided with a suitable lining f⁷ which may be in sections and correspondingly adjustable in 80 any suitable manner. When the centering is adjusted longitudinally it may be held by any suitable means, as a screw on a collar f⁸ passing into a strip f, the collars being shown as provided with holes f⁹ for this purpose. By means of such centering a partition or girder of suitable length and width 85 may be constructed simultaneously and integrally with the floor.

At the ends of the girder-centering the 90 collars are made somewhat deeper than the intermediate ones, and rest upon the clamping strips and filling pieces of the mold for the column, as shown in Fig. 3. The ends 95 of the bottom strips terminate short of the 100 sides, and inclined brackets f¹⁰ connect the ends of the two extreme bottom strips to the end-collars and support an inclined filling-piece f¹¹ upon which an inclined extension f¹² of the lining rests. The space between 105 the ends of the two centerings is closed by an extension a⁶ of one of the sections of the column-mold.

The stanchions B' are provided at their 110 tops with intermediate pieces b⁹ and with side-pieces b¹⁰ to widen their tops to receive 115 the joists and also to hold the joists in place, suitable collars or strips b¹¹ being employed to secure the several parts.

In the construction shown in Fig. 1 four 120 pillars A are illustrated arranged at suitable distances to produce a rectangular form of floor, and upon the completion of the centerings for the pillars, in the centerings for the girders and spread over the floor of the panel-centering so that suitable pillars, 125 girder and floor panel or slab are simultaneously and integrally constructed. As all parts are constructed in knockdown form they may be disassembled and taken apart with ease and rapidity and without the ne- 130

cessity of removing any nails or temporary fasteners whereby the parts if made of wood would be rapidly destroyed, and they may again be easily and readily assembled for the

5 next or successive use.

Owing to the adjustability of the stanchions the centerings may be set at any elevation for floors of different height, and owing to the adjustability of the joists and 10 cross-beams they may be made in suitable sizes or areas, the floor-slats being likewise adjustable for this purpose. The girder centerings may be correspondingly adjusted to provide girders of length corresponding to 15 the distances between the columns or other supports, and they may also be adjusted transversely to provide girders of different widths.

Having described my invention what I 20 claim as new and desire to secure by Letters Patent of the United States, is—

1. In a device of the class described, an adjustable structure comprising a series of adjustable joists, a series of adjustable cross-beams arranged transversely on the joists, a series of adjustable floor-slats on the cross-beams, a sheet metal covering, and a longitudinally adjustable girder-centering of greater depth than the width of the joists, 25 beams and slats.

2. In a device of the class described, a series of adjustable stanchions, a series of adjustable joists carried thereby, a series of adjustable cross-beams carried by the joists, a 30 series of adjustable floor-slats carried by the

cross-beams, said slats being arranged in banks or groups, and longitudinally adjustable girder-centerings carried on the stanchions.

3. In a device of the class described, a series of stanchions, a series of joists, each joist composed of telescopic sections, a series of cross-beams arranged transversely of the joists, each cross-beam being composed of telescopic sections, a series of floor-slats 45 arranged transversely of the cross-beams, the slats being connected in adjustable banks or groups, and a sheet metal covering.

4. In a device of the class described, adjacent floor centerings, and a girder centering 50 comprising two sides and a bottom composed of strips or pieces alternately movable longitudinally with respect to each other, and collars connecting alternate strips.

5. In a device of the class described, adjacent floor centerings, and a girder centering having side walls and a bottom, and a sectional collar connecting the sides and bottom, one section of the collar carrying one side wall and the bottom and the other section 60 of the collar carrying the other side wall, and means to secure the sections in adjustable relation.

In testimony whereof I affix my signature in presence of two witnesses.

LAWRENCE G. HALLBERG.
